CLAIM

The ornamental design for a mail delivery indicator for a mailbox, as shown and described.

DESCRIPTION

FIG. 1 is a front perspective view of a mail delivery indicator for a mailbox, showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is another perspective view thereof, shown in a used condition with a mailbox in broken lines;

FIG. 9 is another perspective view thereof, shown in a used condition with a mailbox in broken lines; and,

FIG. 10 is another perspective view thereof, shown in a used condition with a mailbox in broken lines.

The broken lines shown in the drawings form no part of the claimed design.

In the drawings, the logos on the two balls forming part of the claimed design is an unregistered trademarks/logos of the inventor, Paul J. Paris.
